Des. 214,143
Patented May 13, 1969

214,143

HOLDER FOR A CARD INDEX OR THE LIKE

Jean-Pierre Goeury, Sceaux, France, assignor to Office d'Etudes et de Diffusion Pharmaceutique & Centre de Recherche et d'Etude Medicale O.E.D.I.P.-C.E.R.E.M., Saligny, Yonne, France

Filed Nov. 14, 1967, Ser. No. 9,406

Claims priority, application France May 16, 1967

Term of patent 14 years

Int. Cl. D19—02, 03

U.S. Cl. D74—2

I claim:

The ornamental design for a holder for a card index or the like, as shown and described.
